SELF-WATERING POT

Angelo Giuseppe Natale Pascucci, Via Venti Luglio,
Guadino Tadino, Italy

Filed Aug. 7, 1972, Ser. No. 278,295

Term of patent 14 years

Int. Cl. D11—02

U.S. Cl. D35—3 A

FIG. 1 is a top plan view of a self-watering pot embodying my new design;

FIG. 2 is an elevational view thereof;

FIG. 3 is a bottom plan view thereof, and

FIG. 4 is a sectional view taken in the direction of line 4—4 of FIG. 2.

I claim:

The ornamental design for a self-watering pot, substantially as shown.
